TYPOGRAPHIC NUMBERING APPARATUS

Filed Nov. 23, 1923

Patented June 21, 1927.

1,633,278

UNITED STATES PATENT OFFICE.

WILLIAM E. C. SANDER, OF HOLLIS, NEW YORK.

TYPOGRAPHIC NUMBERING APPARATUS.

Application filed November 23, 1923. Serial No. 676,475.

Among the principal objects which the present invention has in view are: To facilitate the adjustment of the machine to various requirements; to protect the resilient parts of the machine; to secure accuracy in the moving parts of the machine; and to adapt the machine to the variation in the work in which it is employed.

Drawings.

Figure 1 is a top plan view of a numbering machine constructed and arranged in accordance with the present invention.

Figure 2 is an end elevation thereof, the retaining gate for holding the operating plunger in position being shown as open or thrown back from its active position.

Figure 3 is a sectional elevation of the machine the section being taken as on the line 3—3 in Fig. 1.

Figure 4 is a cross section of the machine, the section being taken on the line 4—4 in Fig. 3.

Figure 5 is a cross section of the plunger, the section being taken on the line 5—5 in Fig. 1.

Figure 6 is a horizontal section on enlarged scale, the section being taken on the line 6—6 in Fig. 5.

Figure 7 is a horizontal section taken on the line 7—7 in Fig. 5.

Figure 8 is a cross section taken on the line 8—8 in Fig. 3.

Figure 9 is a perspective view of the end of the casing in which the operating plunger is mounted.

Description.

The apparatus herein disclosed is principally used in printing presses to imprint progressively, increasing or decreasing numerals successively.

To this end an approved form of numbering mechanism, wherein printing wheels such as indicated by the numerals 10, 11, 12, 13, 14 and 15, are employed. The said wheels are rotatively mounted upon a shaft 16 upon which is pivotally mounted a swing 17.

The arms 18 and 19 pivoted on the shaft 16 support the cross bar of the swing 17. A shaft 20 is mounted on the arms, and a pawl 21 is secured thereto. The pawl is provided with various lengths of teeth 22 which successively drop into the deep ratchet tooth with which each of the wheels is pro-

vided. Each wheel is provided with a series of ten embossed numerals, arranged from zero to nine inclusive. The wheels are rotated step by step successively as the pawl advances and recedes and each wheel moves thru one space as the preceding wheel makes a complete revolution.

To rock the swing 17 and pawl 21 connected therewith the arm 18 is provided with a circular extension 23, shaped to extend between the bracket arms 24 of a reciprocating plunger 25. The plunger 25 makes provision for installing the variable type heads 26. This is best shown in Figures 1 and 5 of the drawings.

A T-slot is formed in the top of the plunger 25. Under the overhang edges 27, the flanges 28 extend. One of the flanges 28 has suitably located therein a niche to receive the end of a detent spring 29 which is mounted in a groove formed in the side of the said plunger.

To remove the type head 26 the free end of the detent spring 29 is retracted to release the said type head when the same may be withdrawn from the T-slot wherein it has been held.

The plunger 25 is normally extended beyond the bed of the type form. In the present construction, the plunger rests or is cushioned upon the spiral spring 30. The spring 30 is housed within a bore formed within the plunger 25 to constitute a guide for the spring case 31. The case 31 is retained in the plunger 25 by a bifurcated U-shaped slide. The slide 32 is best shown in Figures 5 and 7 of the drawing. The slide 32 rests in a groove formed in the wall of the plunger 25 and in the cut-away sections 33 in the sides of the case 31.

The moving members of the apparatus heretofore described are mounted in a housing formed by an open-centered base 34 having at one end thereof the upstanding side 35 at one end to support the shaft 16, the opposite end thereof is supported by an upstanding partition 36, as is best seen in Figures 1 and 3 of the drawings.

The partition 36 in the present invention forms one side of a box in which the plunger 25 is mounted in service. The plunger 25 is held within the box formed by the said partition 36 and the sides 37 and 38, by a spring closed gate 39. The gate 39 as shown in Fig. 2 of the drawings has a closure spring 40 which surrounds the hinge pin of

the gate 39. The spring 40 is sufficiently strong to prevent the accidental or unintentional removal of the plunger 25.

The overhanging side 41 on the said gate 6 furnishes means for opening the same for the removal and replacement of the plunger 25 and also acts as a lock when the machine is clamped in press by furniture which bears on side of case.

16 With an apparatus constructed and arranged as described, it is obvious that the type head 26 may be quickly and readily changed for replacement by holding back the end of the detent spring 29, while the said head is pressed out of engagement with the overhanging edges 27 of the plunger 25.

When the type head is inserted in the T-slot it is quickly adjusted in place, the detent 29 striking into the niche in the flange 28 of the said type head.

As seen best in Fig. 6 of the drawings, provision is made for centering the type head by means of the spring 29, the sides of the niche into which the said spring drives 25 being outwardly flared. This flared construction presents a rigid setting of the type head.

To displace the spring 29, the end of the flange 28 having the niche cut therein, is 30 rounded off or chamfered, as can be seen in Fig. 6. This portion of the flange 28 wedges under the free end of the spring 29, displacing it until the niche in the flanges registers with the spring to permit its entrance thereinto.

The type head being placed in position, the plunger 25 carrying the same is placed in operating position, the gate 39 being 40 opened to admit the plunger between the sides 37 and 38. When the plunger is placed between the sides 37 and 38, it is so guided that the arms 24 pass to the opposite sides of the circular extension 23 and rest on the edges thereof. The bottom of the spring 45 casing 31 rests on the base of the housing 34, as can be best seen in Figures 2 and 3 of the drawings.

The spring 30 when not compressed extends the plunger upward until the slide 32 50 engages the upper edge of the cutaway sections 33. The apparatus in this condition is placed in a printing press form for operation.

It will be observed that as the type head 26 55 is forced upon the work being printed, the plunger contracts the spring 30 until the embossed type members with which the wheels 10 to 15 inclusive are provided press upon the said work. With the relative depression 60 of the plunger 25, the swing 17 and pawl 21 mounted thereon is retracted about the shaft 16, the said pawl passing over detents or ratchet teeth formed integral with the said wheels 10 to 15. When now the pressure 65 incident to the operation of printing is re-

lieved from the plunger 25, the said plunger is lifted by the spring 30 and the bracket arms 24 engaging the circular extension 23 rotates the arms 18 and 19 and advances the swing 17 and pawl connected therewith. 70 This pawl now engages, if permitted, the wheels 10 to 15 inclusive with which it is associated.

If it becomes necessary or desirable to replace the type head 26 or to remove the 75 plunger 25 for substitution thereof, this is easily and quickly accomplished by taking the housing 34 from the printing form when by throwing back the gate 39, the plunger may be withdrawn from the box partly 80 formed thereby and another can be placed in its position with ease and celerity.

I claim:

1. A numbering apparatus having a series of type wheels each wheel being provided 85 with a series of ten embossed numerals, serially arranged from zero to nine inclusive; means for rotating said wheels step by step successively, and the movement of each wheel through one space corresponding with one 90 complete revolution of the preceding adjacent wheel; and means for rotating said wheels, said means embodying a rocking member having a pawl for engaging said wheels at intervals equal to the spaces on 95 said wheels, said rocking member swinging external and adjacent to said wheels and centrally thereto, and a resilient plunger for engaging said rocking member to rock same when said plunger is depressed, and a spring 100 closed member for holding said plunger in operating position.

2. A numbering apparatus having a series of type wheels each wheel being provided with a series of ten embossed numerals, serially arranged from zero to nine inclusive; means for rotating said wheels step by step successively, and the movements of each wheel through one space corresponding with one complete revolution of the preceding adjacent wheel; and means for rotating said wheels, said means embodying a rocking member having a pawl for engaging said wheels at intervals equal to the spaces on said 110 wheels, said rocking member swinging external and adjacent to said wheels and centrally thereto, and a resilient plunger for engaging said rocking member to rock same when said plunger is depressed, and a spring 115 closed member for holding said plunger in operating position, said member embodying a gate hingedly mounted on side members 120 extended from the frame holding said wheels to form a box-like structure, and having an overhanging side for locking said gate. 125

3. In an apparatus such as described, a yielding type holding member; a resilient support therefor embodying a coil spring housed within said type holding member, and a tubular supporting member for holding 130

said spring member, said tubular member being slidably mounted in said holding member and said tubular member being retained in said type holding member by suitable 5 staple presenting a compact operating unit.

4. In an apparatus such as described, a yielding type holding member; a resilient support therefor embodying a coil spring housed within said type holding member, and 10 a tubular supporting member for holding said spring member, said tubular member being slidably mounted in said holding member and said tubular member being retained in said type holding member by suitable staple 15 presenting a compact operating unit; a loose type head having laterally extended flanges; means embodying overhanging members on said holding member for engaging said flanges; and a detent spring mounted on said holding member to bear upon said type member to hold the same in service position.

20 5. In an apparatus as characterized, a yielding elevating type holder having self-

contained elevating means; a box-like container for said type holder, said container 25 having a removable side for permitting the withdrawal of said type holder at will.

6. In an apparatus as characterized, a yielding elevating type holder having self-contained elevating means; and a box-like 30 container for said type holder, said container having a removable side for permitting the withdrawal of said type holder at will, said side having locking means for holding said type holder in service when desired. 35

7. In an apparatus as characterized, a yielding elevating type holder having self-contained elevating means; and a box-like container for said type holder, said container having a removable side for permitting the 40 withdrawal of said type holder at will, said side having locking means for holding said type holder in service when desired, said means embodying a spring for closing said side on said container.

WILLIAM E. C. SANDER.
